UNITED STATES PATENT OFFICE.

BAYLUS CADE, OF SHELBY, NORTH CAROLINA, ASSIGNOR TO CADE MANUFACTURING COMPANY, OF SHELBY, NORTH CAROLINA, A CORPORATION OF NORTH CAROLINA.

CASTING MECHANISM FOR TYPOGRAPHICAL MACHINES.

1,326,477.

Specification of Letters Patent.

Patented Dec. 30, 1919.

Original application filed June 10, 1915, Serial No. 33,382. Divided and this application filed November 15, 1917. Serial No. 202,205.

To all whom it may concern:

Be it known that I, BAYLUS CADE, a citizen of the United States, residing at Shelby, in the county of Cleveland and State of North Carolina, have invented new and useful Improvements in Casting Mechanism for Typographical Machines, of which the following is a specification.

The present invention relates to improvements in line casting machines and more particularly to those of the class shown and described in my Patent No. 1,257,185, granted February 19, 1918, of which the present is a division.

15 The primary objects of the invention are to provide an improved casting mechanism which includes vise jaws and alining bars which gather together the selected matrices, aline and clamp them before the mold, and 20 a mold composed of sections which come together endwise before the line of assembled matrices to form the mold cavity and which after the cast separate and thereby enable the slug to be readily ejected 25 therefrom.

To these and other ends, the invention consists in certain improvements, and combinations and arrangements of parts, all as will be hereinafter more fully described, the 30 novel features being pointed out particularly in the claims at the end of the specification.

In the accompanying drawings:—

Figure 1 is a side elevation of a line composing and casting machine constructed in accordance with the present invention.

Fig. 2 is a perspective view of casting mechanism and matrix gathering, clamping and alining devices, constructed in accordance with the present invention.

Fig. 3 is a detail view of the mold and its coöperating parts and also the operating means for the casting mechanism.

Fig. 4 is a detail view of the lock which 45 controls the operation of the metal pot.

Fig. 5 represents a longitudinal section through the casting mechanism.

Fig. 6 is a top plan view of the same.

Fig. 7 is a detail view showing the mechanism for operating the alining bars and vise jaws and the mold sections as well as the means for operating the slug ejector and related parts.

Fig. 8 is a detail view of the justifying slide.

55

Fig. 9 is a perspective view of the same.

Fig. 10 is a detail view of the cam which controls the reciprocating movements of the matrix sectors.

60 Fig. 11 is a detail perspective view of the slug trimming mechanism.

Casting mechanism embodying the present invention may be used generally in conjunction with machines of different types for assembling and composing lines of matrices 65 from which slugs are to be cast, although the particular embodiment of the casting mechanism shown herein is especially adapted for use in conjunction with a line composing machine of the class shown and 70 described in my application hereinbefore referred to. Inasmuch as the present application pertains to the casting mechanism only, it is unnecessary to describe in detail herein the matrix assembling mechanism, reference 75 being made to said prior application for a detailed illustration and description thereof, it being sufficient to state that the matrices 1 from which the slugs are cast are carried by a set of rotatable sectors 2, that 80 the sectors are set in different positions by matrix selecting mechanism 3 arranged at one side of the periphery of the sectors, and that when the desired matrices have been selected, they will be arranged in a row and 85 are adapted to be moved outwardly radially of the sectors into coöperative relation with the casting mechanism.

The casting mechanism in the present instance is mounted on a frame 5 which is 90 supported on the base frame 6 of the machine and in a position substantially diametrically opposite to the selecting mechanism. The vise and mold, however, are mounted on a bracket 297 which projects 95 rearwardly from the frame 7 which supports the matrix sectors and their selecting mechanism. The bracket 297 supports a rail 298 which extends transversely of the machine, and a pair of slides 299 and 300 100 are mounted to reciprocate in unison toward and from one another on said rail, the approaching and receding movements of the slides being effected by a screw 301 which embodies right and left-hand threads 105 engaging the respective slides, the outer

end of the screw shaft having a pinion 302 thereon which is connected through the train of gears 303, 304 and 305 to a pinion 306, the latter coöperating with a gear sector 307 carried at the outer end of an arm 308. Said arm 308 is pivoted at 309 and carries a roller or projection 310 which co-
operates with an operating cam 311, said cam being mounted on a shaft 221 and
10 driven by a pair of coöperating gears 314 and 315, the gear 315 being fixed to an in-
termittently revolving shaft 316, the opera-
tion of which is controlled in the manner
described in my prior application.

15 The slides 299 and 300 carry a pair of complementary mold sections 324 and 325, the mold section 325 having a recess 326 which, when the mold sections are brought together, will be opposite to the flat portion 324a of
20 the mold section 324 and will thus produce a mold cavity in which the slug is cast. The slides 299 and 300 also carry a pair of vise jaws 327 and 328 which are adapted to gather together the selected matrices when they have been brought to a position in front of the casting mechanism and to clamp them in a line of the desired length. A pair of complementary alining bars 329 and 330 project from the inner sides of the vise jaws, these alining bars entering the ap-
25 tures in the bodies of the selected matrices whereupon the approaching movement of the vise jaws is interrupted, the matrix carrying sectors are shifted forwardly, thereby causing the selected matrices to be drawn out a suitable distance from the peripheries of the sectors, and while the latter are in their forward position the approaching movements of the vise jaws are resumed, whereupon the vise jaws gather together the line of matrices into a line of the de-
30 sired length, this being permitted by the flexible stems supporting the matrices. The final closing movements of the vise jaws cause the alining bars 329 and 330 to produce accurate alinement of the matrices. In order to maintain the proper relation be-
35 tween the alining bars 329 and 330, they are preferably formed on their coöperating faces with ribs 331 and 332 and corresponding grooves 333 and 334.

30 The mold sections 324 and 325 are movable laterally with relation to the corresponding vise jaws 327 and 328. In the present instance, the mold sections are supported on pins 335 and 336, and springs 337 and 338 operate to normally force the mold sections rearwardly with relation to the vise jaws. The mold section 325 is provided with
35 an ejector for removing the slug therefrom. In the present instance, this ejector is in the form of a spring plunger 339 which extends through the top of the mold so as to operate to push the slug out of the recess 326. The
40 ejecting pin or plunger 339 is depressed at
45

the proper time by an arm 340 which is fixed to a shaft 341, said shaft being rocked at appropriate intervals by an arm 342 fixed thereto, a link 343, an arm 344 to which said link is connected, said arm 344 being pivoted to the frame at 345, and a link 346 which in turn is reciprocated at proper intervals by an appropriate part of the ma-
50 chine.

55 349 designates a galley to receive the slugs 75 after they have been cast and trimmed. The galley is provided with a reciprocating follower 350 for advancing the slugs therein and to provide room to accommodate the incoming slugs which enter the galley end-
60 wise through a slot 351 formed in the inner side wall of the galley. The follower is reciprocated by a link 352 which is attached thereto and an arm 353 which is fixed to the ejector shaft 341. The slugs are trimmed by the passage thereof endwise through a trimming knife 354 which, as shown, is three-sided and operates to trim the two flat sides and the foot or bottom of the slug, the trimming knife being in alinement with the slot 351 leading to the galley. The slugs are successively positioned to enter the trimming knife by a slug receiver 355, and the slugs are pushed from this receiver through the trimming knife by a blade 356 which is carried by or forms a part of the slide 300. The slug receiver is movable from a position to receive the slug from the mold to a position before the trimming knife. In the construction shown the slug receiver is fixed to a shaft 357 and this shaft is operatively connected to the ejector shaft 341 by the gears 358 and 359. When the mold section 325 has been retracted with a slug contained in the recess 326 therein, the slug receiver 355 is swung upwardly to a position beneath said mold section and the ejector then operates to remove the slug from the mold section 325, causing it to drop into the slug receiver. When the slug receiver swings downwardly into the position shown in Figs. 5 and 11, the slug in the receiver is then in alinement with the trimming knife and the blade 356, and movement of the blade 356, which is carried by the slide 300, 100 toward the trimming knife causes the slug to pass through the trimming knife and the slug in advance of the one just trimmed is pushed into the galley. In order to bring the mold section 325 into a position directly above the slug receiver, a lever 360 is provided, it being pivoted at 361 on a stationary bracket 362 and it has a hook 363 at one end to engage the rear side of the mold section 325 while its opposite end is arranged to be engaged by a projection 364 on the ejector shaft 341 so that rotation of the ejector shaft in a direction toward the ejector 340 to eject the slug from the mold section 325 will simultaneously operate the 105
110
115
120
125
130

lever 360 in a direction to push the mold section 325 forwardly against the action of its spring 338, thereby bringing this mold section into a position directly above the 5 slug receiver.

Justification of the line of matrices is effected by pushing upwardly the wedges of the spacers which have been fed into the line at appropriate intervals. The expanding or pushing upwardly of the wedges of the spacers is effected by a vertical wedge-expanding slide 365 which is mounted to reciprocate vertically in guides 366 mounted on the bracket 297, and this wedge-expanding 10 slide is operated through a link 367 and an arm 368, the latter being fixed on a rock shaft 369. The rock shaft 369 is provided with an actuating arm 370 which is fixed thereto, and the arm 370 is connected 15 by the link 371 to an arm 372, the latter being fulcrumed or pivoted at 373 and is provided with a roller 374 which is adapted to follow an internal cam 375 mounted on the shaft 53. The roller 374 is pressed yield- 20 ably toward its cam by a spring 377 which is connected to the rock shaft 369 through the elements 370, 371 and 372 and is of sufficient strength to force the wedges upwardly to effect justification, the cam determining 25 the period at which justification will be effected and serving to retract the wedge-expanding slide.

378 designates a metal pot which may be of the type generally used in machines of this class, it having a spout 379, the mouth of which is adapted to engage and close the rear side of the mold, and a plunger 380 serves to eject metal from the pot through the spout and into the mold. The plunger 30 is operated by a plunger arm 381 which is pivoted to the pot at 382, a weight 383 being mounted on the arm 381, providing the power required in actuating the plunger. The casting operation is controlled by a 35 lever 384 which is pivoted at 385 to the base 6 and carries a roller 386 which cooperates with an appropriately shaped cam 387 whereby the weighted arm 381 and the plunger attached thereto will be permitted 40 to drop and to force molten metal into the mold at the moment the mold sections have been closed in front of the line which is clamped between the vise jaws.

Means is provided for controlling the operation of the plunger 380 in order to prevent ejection of metal from the pot should an incomplete line of matrices be presented at the casting point. Should the line of matrices be incomplete, then the wedge-expanding 45 slide 365 would rise to an abnormal degree as the wedge spacers would be unable to fill up or complete the line and the forcing of metal into the mold would cause squirting of the metal through the spaces 50 left between the matrices of the loose or

incomplete line. In the construction shown, the shaft 382 to which the plunger actuating arm 381 is connected has a dog 388 fixed thereto and arranged to coöperate with a finger 389, the latter being pivoted to the 55 metal pot at 390 and connected at its lower end by a link 391 to a lever arm 392, the latter being rigidly connected by the shaft 393 to a latch 394. This latch has a projection 395 which is adapted to rest upon the periphery of a sector 396, the latter being loosely mounted on the shaft 369 and is movably connected to a second sector 397 by a pin 398 on the latter which works in a slot 399 in the loose sector 396, the sector 80 397 being fixed on the shaft 369. The projection 395 on the latch 394 is wide enough to also rest upon the periphery of the sector 397. The sector 396 is formed with a notch 400 which is adapted to move into a position 85 to receive the projection 395 during the normal stroke of the wedge-expanding slide 365, but should the wedge-expanding slide rise abnormally, the notch 400 will be carried past the projection 395 and the latch 90 394 will then be held in elevated position. While the latch 394 is in its elevated position, due to the resting of the projection 395 on the unnotched periphery of either the sector 396 or the sector 397, the finger 95 389 will occupy a position beneath the free end of the dog 388, and the latter will thereby lock the metal ejecting plunger 380 and thus prevent operation thereof, but when the projection 395 rests in the notch 400, 100 the finger 389 is clear of the dog 388, as appears in Fig. 4, and the plunger 380 is then unlocked and free to operate. The latch 394 is held in coöperative relation with the sectors 396 and 397 by a spring 401. 105

After the mold sections have been brought together in front of the line of matrices, the metal pot is moved forwardly to bring the mouth of the spout thereof against the rear side of the mold, the cast then taking 110 place after which the metal pot recedes preparatory to the separation of the mold sections. To this end, the metal pot is formed with a base 402 which is slidable in a forward and rearward direction in horizontal 115 guides 403 formed on the top of the frame 3. A cam 404 is fixed to the shaft 376 and is appropriately shaped to produce the forward and rearward movements of the metal pot, as described. An arm 405 is mounted 120 on the shaft 373, it having a roller 406 which follows the groove of the cam 404, and the arm 405 is operatively connected to a lever 407, the upper end of the latter being connected to the metal pot. 125

The shaft 376 which carries the cams which control the justification, the movements of the metal pot toward and from the mold, the actuation of the plunger which forces the metal into the mold, and the op- 130

eration of the rod 47 which controls the relative timing of the operations of the casting mechanism and the matrix selecting mechanism, is driven by a sprocket wheel 5 408 and a coöperating chain 409, the latter being operated by appropriate parts of the machine as described by my prior application.

I claim as my invention:—

10 1. In a machine of the class described, the combination with a plurality of carriers each bearing a set of matrices each having an aperture therein, of a pair of complementary vise jaws movable toward one another to 15 clamp a line of matrices and carrying complementary alining bars arranged to enter the apertures in the matrices.

20 2. In a machine of the class described, the combination with a plurality of carriers each bearing a set of matrices each having an aperture therein, of a pair of oppositely movable alining bars adapted to enter the apertures in a line of the matrices, said alining bars having slidably engaged ribs and 25 grooves.

30 3. In a machine of the class described, the combination with a plurality of matrix carriers, of a pair of longitudinally movable complementary mold sections shiftable transversely of the paths of movement of the matrix carriers, one mold section having a recess which forms with the coöperating mold section a mold cavity.

35 4. In a machine of the class described, the combination with a plurality of matrix carriers, of a pair of oppositely movable complementary mold sections, one mold section having a recess which forms with the coöperating mold section a mold cavity, and a 40 slug ejector carried by the recessed mold section.

45 5. In a machine of the class described, the combination with a plurality of matrix carriers, of a pair of oppositely movable complementary mold sections, one mold section having a recess which forms with the coöperating mold section a mold cavity, and a pivoted slug receiver movable to and from a position beneath the recessed mold section.

50 6. In a machine for casting a type slug from a line of matrices having alining apertures formed therein, a pair of complementary vise jaws movable relatively in a direction toward and from one another to clamp and 55 release a line of matrices, and complementary alining bars relatively movable in unison

with the vise jaws to enter the alining apertures in the line of matrices.

7. In a machine for casting type slugs from lines of matrices, a pair of complementary mold sections relatively movable longitudinally in a direction toward and from one another, one section having a longitudinal recess which forms with the coöperating mold section a mold cavity.

60 8. In a machine for casting type slugs from lines of matrices, the combination of a pair of complementary vise jaws relatively movable in a direction toward and from one another to clamp a line of matrices between them, and a pair of complementary mold sections relatively movable in a direction toward and from one another in unison with the movements of the vise jaws and coöperating when in one position to form a 70 mold cavity, the mold sections being also movable laterally relatively to the respective vise jaws to carry the mold into co-operative relation with a line of matrices clamped between the vise jaws.

75 9. In a machine for casting type slugs, the combination of a pair of complementary mold sections relatively movable in a direction toward and from one another, one section having a recess adapted to form with the coöperating mold section a mold cavity, an ejector carried by said recessed mold section and operative to eject a slug laterally therefrom when the mold sections are relatively separated, and an ejector-actuating member operative upon the ejector when the recessed mold section is in retracted position.

80 10. In a machine for casting type slugs, the combination of a slug casting mold embodying oppositely movable complementary sections, one section being recessed to form with the other section a mold cavity, a slug receiver pivoted to swing into a position to receive a slug from the recessed mold section and to carry the slug into a discharging position, and a blade movable with the recessed mold section for discharging the slug from the slug receiver while the latter is in discharging position.

85 105 In testimony whereof I have hereunto set my hand in presence of two subscribing witnesses.

BAYLUS CADE.
